DESIGN FOR A SACHET POWDER CONTAINER OR SIMILAR ARTICLE

Joseph S. Stein, Chicago, Ill., assignor to Lucien Lelong Inc., Chicago, Ill., a corporation of Illinois

Application December 30, 1936, Serial No. 66,800

Term of patent 3½ years

To all whom it may concern:

Be it known that I, Joseph S. Stein, a citizen of the United States, and a resident of the city of Chicago, county of Cook, and State of Illinois, have invented a new, original, and ornamental Design for a Sachet Powder Container or Similar Article, of which the following is a specification, reference being had to the accompanying drawing forming a part thereof.

On the drawing:

The characteristic feature of the design resides in the specific elements of ornamentation arranged in the specific pattern shown and on the sachet powder container shown.

I claim:

The ornamental design for a sachet powder container or similar article as shown and described.

JOSEPH S. STEIN.
